(57) CLAIM

The ornamental design for a punch, as shown and described.

DESCRIPTION

FIG. 1 is a top, front, right perspective view of a punch according to my invention;

FIG. 2 is a top, front, left perspective view thereof;

FIG. 3 is an enlarged perspective view of area A in FIG. 2, shown in a retracted position;

FIG. 4 is an enlarged perspective view of area A in FIG. 2, shown in an extended position;

FIG. 5 is a front view thereof;

FIG. 6 is a rear view thereof;

FIG. 7 is a right side view thereof;

FIG. 8 is a left side view thereof;

FIG. 9 is a top plan view thereof; and,

FIG. 10 is a bottom plan view thereof.

The broken lines shown in the Figures illustrate portions of the punch that form no part of the claimed design.
